US0D1102921S

(12) **United States Design Patent** (10) **Patent No.:** **US D1,102,921 S**
(45) **Date of Patent:** **** Nov. 25, 2025**

(54) **DISTANCE AREA AND POSITION
MEASURING INSTRUMENT**

(71) Applicant: **ETO GRUPPE TECHNOLOGIES
GmbH**, Stockach (DE)

(72) Inventors: **Walter Naumann**, Immenstaad (DE);
Benjamin Bönisch, Bodman (DE)

(73) Assignee: **ETO GRUPPE TECHNOLOGIES
GmbH**, Stockach (DE)

(**) Term: **15 Years**

(21) Appl. No.: **29/913,336**

(22) Filed: **Sep. 29, 2023**

Related U.S. Application Data

(62) Division of application No. 35/514,598, filed on Apr. 8, 2022 (U.S. filing date under 35 U.S.C. 384), and having an international filing date of Apr. 8, 2022, now Pat. No. Des. 1,015,908.

(57) **CLAIM**

The ornamental design for a distance area and position measuring instrument, as shown and described.

DESCRIPTION

FIG. 1 is a top plan view of a distance area and position measuring instrument showing our new design, the bottom view, not shown, is a mirror image thereof;

FIG. 2 is a perspective view thereof;

FIG. 3 is a left side elevational view thereof;

FIG. 4 is a right side elevational view thereof; and,

FIG. 5 is a front view thereof.

The portions of the rear view of the distance area and position measuring instrument not illustrated are plain and unornamented and form no part of the claimed design.

1 Claim, 5 Drawing Sheets
